MARTIN KRUMM, JR., OF COLUMBUS, OHIO.

Letters Patent No. 76,637, dated April 14, 1868.

IMPROVEMENT IN CONSTRUCTION OF FENCE-POSTS.

The Schedule referred to in these Letters Patent and making part of the same.

TO ALL WHOM IT MAY CONCERN:

Be it known that I, MARTIN KRUMM, Jr., of Columbus, in the county of Franklin, and State of Ohio, have invented a new and useful Improvement in the Construction of Fence-Posts; and I do hereby declare that the following is a full, clear, and exact description thereof, reference being had to the accompanying drawings, making part of this specification, in which—

Figure 1 is a perspective view of a fence constructed with my improved posts.

Figure 2 is a vertical sectional view of two fence-posts differing slightly in form from those shown in fig. 1.

Figure 3 shows a fence-post of a U-form, it being a modification of the posts of figs. 1 and 2.

Similar letters of reference indicate corresponding parts in the several figures.

This invention is designed to provide for the expansion and contraction of metal fences of every style and description, and, at the same time, have all the parts composing such fences rigidly secured together. I am aware that, prior to my invention, several attempts have been made to construct metal fences, with provision for contraction and expansion, but this has been done at the expense of strength and rigidity, and, as far as I am aware, such attempts have never been successful.

A good metal fence should have its parts rigidly secured together, the posts should be rigidly fastened at their bases into a solid foundation, and the horizontal rails, or the panels between the posts, should be rigidly fastened to the posts. A good metal fence should also be so constructed that whatever its length may be, the rails or horizontal rods should be allowed to extend and contract by the influence of climatic changes upon the fence.

To effect these objects in a single fence, the nature of my invention consists in a laterally-springing post, made of bar or strap-metal, bent in such manner that, when the post is secured in place to a suitable base-piece, its limbs may be pressed nearer together, or drawn further apart, to an extent which will admit of an unrestrained contraction and extension of all horizontal tie rails or bars used between the post, as will be hereinafter described.

The invention also consists in constructing a fence-post of one or more pieces of metal bent in such manner as to afford ornamental spring-heads, or both head and foot-pieces, so that such ornament or ornaments will not only serve to beautify the fence, but will also allow the limbs of the post to be extended and contracted transversely to any desired extent, as will be hereinafter described.

To enable others skilled in the art to understand my invention, I will describe its construction and operation.

In the construction of my improved fence-posts, I prefer to employ an article known in the market as flat-bar or strap-iron, although the posts may be made of rods of any metal, and of any desired size and shape in cross-section. I prefer to employ the rods or strap-iron as furnished by the trade, because the only labor required to produce the posts of these rods is to cut and bend them to the required shape.

I take a rod of the proper length, and double it by bending it around a horn of cylindrical form, thus producing an open, U-shaped post, J, as shown in fig. 3. The rounded end g of this post forms its upper end, and the open end is embedded into a stone, or other suitable base, D, as shown. This is the simplest form of yielding post, and may be used interposed between more ornamental posts. Another form of post may be made, possessing greater elasticity transversely, by bending the upper end of the post in the manner represented at A', in figs. 1 and 2; and, if still greater elasticity is required, the bottom ends of each post may be curyed and brought together, as shown at c, in figs. 1 and 2.

It will be seen that each post shown in the drawings is made of one piece of flat metal, and that its ornamental end is made by bending the metal around suitable form-pieces, leaving the upright body-portions of the post straight and parallel to each other, so that these parallel portions may be extended or contracted transversely.

By enlarging or flattening the end or ends of each post, it will be seen that they will afford greater spring-action than is allowed by the bars J, which are united at their upper ends by the single bend or arch g, shown

in fig. 3. At the same time, by thus terminating the end or ends of the post, I am enabled to produce a variety of ornamental designs, which will add greatly to the beauty of a fence composed in part of such posts.

I prefer to construct each one of my spring or yielding posts of one piece of metal, bent substantially as described, but, if desired, each post may be constructed of longitudinal sections riveted together.

When posts of the above-described construction are properly erected upon a solid base, D, the horizontal rails B B are secured rigidly to them, by means of nuts and screws, or by riveting the ends of these rails to the posts. Pickets C, or other suitable filling, may then be applied to the rails, in the usual well-known manner. The posts being open, as shown, they will afford convenient access to the ends of the rails B, for screwing or riveting these ends to the post-bars. It will be seen that the rails B do not pass entirely through the posts, but terminate inside of each one of the limbs of each post, with shoulders formed near their ends, which abut against the outer sides of the limbs of the posts, so that when the nuts *a a* are applied upon the screws which are formed on the ends of the rails, and these nuts forcibly tightened, rigid joints will be made. Thus it will be seen that the rails B are allowed perfect freedom to extend and contract by the yielding of the limbs of the posts.

While I prefer to adopt the U-shaped post, with or without ornamental ends, I do not confine myself to this precise form of posts, as transversely-expansible posts may be made of a variety of forms, with or without ornamental figures.

Having described my invention, what I claim as new, and desire to secure by Letters Patent, is—

A transversely-expansible post, A, having its vertical portions united at the top by one or more springs, A', substantially as shown and described.
